(57) **CLAIM**

The ornamental design for a photography light as shown and described.

DESCRIPTION

1. Photography light

FIG. 1.1 is a front, top perspective view of a photography light embodying our new design;

FIG. 1.2 is a rear, bottom perspective view thereof;

FIG. 1.3 is a front elevation view thereof;

FIG. 1.4 is a left side elevation view thereof;

FIG. 1.5 is a right side elevation view thereof;

FIG. 1.6 is a rear elevation view thereof;

FIG. 1.7 is a top plan view thereof;

FIG. 1.8 is a bottom plan view thereof; and

FIG. 1.9 is an enlarged view of portion 9 shown in FIG. 1.1. This photography light is used for photography to provide lighting.

The broken lines in the drawings depict portions of the Photography Light that form no part of the claimed design.
